UNITED STATES PATENT OFFICE.

AMOS F. REISTE, OF PANTHER, IOWA.

FENCE-STAY.

SPECIFICATION forming part of Letters Patent No. 554,005, dated February 4, 1896.

Application filed August 31, 1895. Serial No. 561,145. (No model.)

To all whom it may concern:

Be it known that I, AMOS F. REISTE, a citizen of the United States, residing at Panther, in the county of Dallas and State of Iowa, 5 have invented a new and useful Fence-Stay, of which the following is a specification.

My invention relates to wire-fence stays, and particularly to improved means of looping the same, whereby a stay is produced 10 which is simple, strong, flexible, light, readily adjusted and which does not interfere with the independent adjustment or removal of the fence-runners and which at the same time produces an elastic, durable and superior fence.

With these and other objects in view my 15 invention consists in the details of construction hereinafter set forth and more definitely pointed out in the claim.

In the drawings, Figure 1 is a perspective 20 view of a section of fence, showing my improvement. Fig. 2 is a vertical section of Fig. 1, showing two links joined together. Fig. 3 is a detail perspective of one of the links before coupling. Fig. 4 is a similar de-

tail after coupling; and Fig. 5 is a cross-section of Fig. 4, taken above the coupled hook 25 and eye.

Referring now to the drawings, in which like parts are designated by like numerals 30 throughout, 1 designates my improved link, which is formed of one piece of wire, preferably spring-wire, and is of a length to correspond to the distance between adjacent line-wires or runners forming the fence. This 35 link 1 is formed by bending an eye 2 lengthwise of the wire and at one end thereof and a hook 3 also lengthwise of said wire and at the other end thereof. Said ends are then bent over on the straight side or back portion 40 of the wire parallel thereto and so as to overlap each other midway the length of said link, the respective loop ends 5 of said link being pinched together to form a neat compact link. Eye 2 lies in a plane transverse 45 to the plane of the link and in a position to receive hook 3, which is bent down sharply at right angles at 6 and is adapted to be normally sprung away from and to extend through eye 2, so as to lap over the outer end 50 7 thereof in line with and across back wire 4.

To complete the operative link, all that now

remains to be done is to spring said hook 3 over the back wire 4. This is all that is desirable in a transient fence, the spring or snap action of the parts holding the hook in 55 place. These links are applied to form a complete stay as follows: One of the free ends of a link, preferably the eye end, is forced through between the twisted top runner or cap-wire 8, and the other end of the link is 60 bent around the next lower runner 9. The hook 3 is then inserted through eye 2 and sprung over back wire 4. A second link is similarly placed over runner 9, passing at the same time through loop 5 of the top link, and 65 the lower end of said second link embracing the next lower runner 10. Successive links are similarly placed, each embracing two runners and being also threaded through the loop end of the preceding link, until all the 70 runners of the fence are linked together. The bottom link is forced between the twisted strands of the bottom runner or base-wire of the fence the same as the top link was fastened.

The object and advantage of thus fastening the two end links of the stay between twisted strands of a cable-wire (or any other variety equivalent for the purpose) and leaving the intermediate links of the stay loose 80 on the intermediate wires are to prevent longitudinal movement of the stay relative to the fence, keeping the stay in true vertical alignment, while at the same time allowing great flexibility in yielding to vertical and 85 side thrusts. Thus if a blow is received by any link that link does not withstand the entire shock, but it yields, transmitting the strain to all links of the stay as well as to the runner-wires. Likewise, if a vertical blow is 90 received all the links and wires above the point of impact sustain the shock, while the links below simply telescope within each other and do not bend or strain themselves or the lower runners. Moreover, the peculiar form 95 of my links reduces the strain at any one point of a link, so that lighter wire may be used and greater strength and durability are attained. The sharp bend 6 and hook 3 distribute the tensile strain throughout every 100 part of the link.

By the use of these improved stays fewer

posts may be used in fence-building than is at present the custom, for the reason that the stays distribute the strains and loads over all the runners or fence-wires, so that no one wire 5 receives the strain, as formerly. The number of stays necessary to be employed depends largely upon the special use and circumstances.

These stays are readily removable for purposes of repair. All that is necessary is to press hook 3 down free from back wire 4, spring it forward slightly, and then press eye 2 down thus releasing the hook entirely and leaving the link free to be bent back out of engagement with the stay and fence. The eye 2 needs to be of a size sufficient only to allow hook 3 to pass therethrough. These links also allow of the ready removal and replacement of any fence-wire without disturbing the others.

My improved links are exceedingly simple in construction, and the fence constructed with them is so simple that no tool or machine is needed in the field other than a pair of ordinary pliers.

Various changes in form, proportion, and the minor details of construction may be resorted to without departing from the principle

ple or sacrificing any of the advantages of this invention.

30

What I claim as my invention is—

In a wire fence, the combination with the line-wires or runners, of a stay, consisting of a plurality of telescoping wire links looped together at their ends and receiving between 35 their looped ends the line-wires or runners, each of said links consisting of a single length of wire bent to form a continuous straight side, and separate terminal portions normally sprung away from said straight side, 40 one of said terminal portions being provided at its extremity with an enlarged eye and the other of said terminal portions being provided at its extremity with a right-angularly-bent arm having an open hook adapted to be 45 pressed through said eye and detachably sprung into engagement with the straight side of the link midway of the looped ends thereof, substantially as set forth.

In testimony that I claim the foregoing as 50 my own I have hereto affixed my signature in the presence of two witnesses.

AMOS F. REISTE.
